UNITED STATES PATENT OFFICE

2,546,592

MOBILE WEED BURNER SYSTEM

Owen L. Garretson and Alvin W. Peck, Bartlesville, Okla., assignors to Phillips Petroleum Company, a corporation of Delaware

Application December 29, 1945, Serial No. 638,407

1 Claim. (Cl. 126—271.2)

1

This invention relates to vaporizers. In one of its more specific aspects it relates to vaporizers for use with liquefied petroleum gases. In a still more specific aspect it relates to vaporizers which are adapted for use in conjunction with tractor-weed burner combinations.

Flame methods for the destruction of weeds have gained in usage in the cultivation of certain crops as a substitute for mechanical cultivation or cutting methods and especially for hand labor methods. It is for the purpose of further extending the use of flame methods for weed killing and/or cultivation in view of economical considerations and savings in labor that our invention is disclosed.

Liquefied petroleum gases are now used as fuel in such weed burning operations and as fuel for internal combustion engines. The use of this type of material as engine fuel presents few problems other than those occasioned by a need for retaining the liquefied fuel under pressure. The rate of evaporation is not sufficiently great as to cause difficulty for engine fuel purposes, but when one source of liquefied fuel is used for the weed burning burners and for a tractor engine, the latent heat of vaporization of the liquid often so chills the liquid that the rate of evaporation is retarded to such an extent that the weed burners do not properly function. It is for the purpose of overcoming this difficulty that our invention is directed.

One object of our invention is to provide a liquid hydrocarbon fuel vaporizer for use with weed burning equipment on a tractor.

Another object of our invention is to provide a liquid hydrocarbon fuel vaporizer for use with weed burning equipment on tractors wherein the vaporizer serves to vaporize fuel for the tractor as well as for the burner.

Still another object of our invention is to provide a liquid hydrocarbon fuel vaporizer for use with weed burning equipment on tractors whereby vaporized fuel, during times of low fuel requirement, is transmitted to points of consumption at a temperature sufficiently low as not to be destructive to delicate equipment with which the fuel vapors come in contact.

Still another object of our invention is to provide a liquid hydrocarbon fuel vaporizer wherein exhaust heat from an engine serves as a source of heat for the vaporization of the fuel.

Still other objects and advantages of our invention will be obvious to those skilled in the art from a careful study of the following description, which taken in conjunction with the at-

2

tached drawing forms a part of this specification.

The drawing represents diagrammatically a preferred form of the apparatus of our invention in conjunction with a tractor-weed burner assembly.

Referring to the drawing, a tractor 1 consists of conventional tractor elements, as wheels 2, an engine 3, a carburetor 4, a body 5, an exhaust pipe 6, a liquid hydrocarbon fuel tank 7, and other parts not specifically shown.

The tractor may be equipped with one or more burners 8 adapted especially to the burning of weeds. The fuel tank 7 is intended to furnish fuel for the weed burners 8 and to the carburetor 15 4 and engine 3 for the propulsion of the tractor. The evaporation of liquefied petroleum gas at rates sufficient for the operation of the weed burners and for the tractor engine has presented a serious problem on account of the refrigeration properties possessed by such normally gaseous hydrocarbons. To solve the evaporation problem we have devised an evaporator 9 which is intended to be operated in conjunction with the exhaust pipe 6 from the tractor engine. 20 Such an evaporator is in reality, a simple mechanism, consisting essentially of an enclosed cylinder having an opening in either end wall for insertion of the exhaust pipe. The enclosed cylinder thus is composed of a cylindrical wall 10 surrounding the exhaust pipe so as to provide an annular space 13 between the wall 10 and the exhaust pipe. End plates 11 serve to close the ends of the cylinder 10 and each plate has an opening for insertion of the exhaust pipe 6. This combination is intended to serve as an evaporating heat exchanger since liquefied petroleum gas from the storage tank 7 flows under its own pressure through a flow line 12 into the annular space 13. This space is maintained at a high temperature by the passage of engine exhaust gases through the exhaust pipe 6 and the heat is utilized in transforming the fuel from the liquid form to the gaseous form, in which form it is suitable for burner and carburetor use.

The exhaust pipes of tractors ordinarily become quite hot, consequently ample heat for this vaporization is usually available even under full burner load conditions. We have found that at times when the weed burners 8 are not in use and evaporation rates are low (for carburetor use only) that the temperature of the evaporated fuel may become excessively high and under certain conditions may destroy such regulator diaphragms and seats as come in contact with the high temperature gas. To prevent such possible

destruction of vital parts, we have provided a cooler 16 for lowering the temperature of the hot gas.

Such a cooler 16 is for the most part a liquid-to-gas heat exchanger and consists of the inner liquid carrying tube 12 and an outer tube 17. The space between these tubes may be termed an annular space and serves to carry the evaporated fuel or hydrocarbon gas from the evaporator 9 to a manifold 18. From the manifold 18 a tube 19 extends to the carburetor 4, and a tube 20 extends to the weed burners 8. Valves 21 and 22 are provided in tubes 19 and 20, respectively, for manual control of flow of gas therethrough. Thus in case it is desired to close off the burners while the tractor is traveling from field to field or from shed to field, etc., valve 22 may be closed.

At the manifold point 18 and at connection points 23 and 24, substantially any type of connections desired may be used. These joints and connections, however, should be of such type and of such materials as to withstand the temperatures of the hot gases and to withstand vibration, stresses and strains characteristic of such equipment.

The fuel tank 7 should preferably be located at a point remote from the burners 8 to minimize dangers resulting from transfer of heat from the burners to the tank. When liquid propane is used as the liquefied petroleum gas fuel, the tank will need to withstand rather high pressure since propane has a Reid vapor pressure of about 180 pounds per square inch (at 100° F.).

A muffler, not shown, may be used on the tractor exhaust if desired, for obvious reasons. If used, however, the muffler should preferably be placed on the downstream side of the evaporator 9 with respect to the direction of flow of exhaust gases.

The relatively cool liquid passing through tube 12 in heat exchange with the hot gases in the annular space 25 has been found to impart sufficient cooling to the gas as to prevent destruction of any fragile and easily burned apparatus parts such as regulator diaphragms mentioned hereinbefore.

This exhaust pipe-vaporizer unit should be well constructed and especially so from the point of view of gas leakage. Exhaust gas should not leak into the vaporizer nor should petroleum gas be permitted to leak into the exhaust pipe.

Materials of construction may be selected from among those commercially available. They should be able to withstand the gas engine exhaust pipe temperature.

As mentioned hereinbefore liquefied propane and even butane must be stored under considerable pressure to retain these hydrocarbons in the liquid state. When using liquid propane as the fuel according to the herein-described invention, the storage tank and pipes or tubes carrying the

propane liquid should be constructed of sufficiently heavy material as to withstand propane pressures. In order to burn propane in the equipment as herein-described, pressure regulators, pressure reducers, automatic valves and the like will need be installed and used at certain points. However, the use of such auxiliary equipment forms no part of our invention, since the use of same is well known to those skilled in the art. Thus, by preference pressure reducers may be located at such points that the propane or other liquefied petroleum gas may be vaporized at substantially atmospheric pressure, or may be vaporized at propane or other storage pressure, as desired.

It will be obvious to those skilled in the art that many modifications of our invention may be made and yet remain within the intended spirit and scope of our invention.

Having described our invention, we claim:

In a mobile weed burning system including an internal combustion engine power plant and a weed burner, a heat exchange system for vaporizing liquefied petroleum gas as fuel for said internal combustion engine and said weed burner, comprising in combination an exhaust pipe extending from said internal combustion engine; a jacket surrounding at least a portion of said exhaust pipe and closed thereon so as to form an enclosed vaporizer chamber therebetween; a liquefied petroleum gas storage tank; liquefied petroleum gas conduit means extending from the lower extremity of said storage tank to said vaporizer chamber; a manifold chamber surrounding said liquefied petroleum gas conduit means and spaced from said vaporizer chamber; a vapor conduit, surrounding said liquefied petroleum gas conduit means so as to form a gas passage therebetween, extending from said vaporizer to said manifold chamber; and outlet conduits extending from said manifold chamber for connection to said internal combustion engine and said weed burner.
